Inventor:
S. D. Payne
of Brindledge
Newbury

United States Patent Office.

SANFORD D. PAYNE, OF KASOTA, MINNESOTA.

Design No. 4,899, dated May 9, 1871.

DESIGN FOR A FRUIT-BASKET.

The Schedule referred to in these Letters Patent and making part of the same.

To whom it may concern:

Be it known that I, SANFORD D. PAYNE, of Kasota, in the county of Le Sueur and State of Minnesota, have invented a new and useful Design in Fruit and Berry-Baskets, and I do declare that the following is a true and accurate description thereof, reference being had to the accompanying photographic illustration and being a part of this specification.

One figure shows a plan of my basket creased for folding, and the other the basket complete.

The basket is intended to be made of stiff paper, square or oblong on top, with two inclined sides, and perforated, to secure ventilation through the fruit and

between the baskets when packed in crates, and so cheap that they may be given away.

Each basket is formed from a single rectangular piece of paper, cut and creased as shown in the first figure, to fold and lock into the form shown in the second.

I claim as my invention—

The design for a fruit-basket, as shown.

SANFORD D. PAYNE.
